H. H. SANFORD,
COMBINED GASEOUS AND SOLID FUEL RANGE,
APPLICATION FILED APR. 24, 1920.

1,377,731.

Patented May 10, 1921.

UNITED STATES PATENT OFFICE.

HENRY H. SANFORD, OF MANSFIELD, OHIO.

COMBINED GASEOUS AND SOLID FUEL RANGE.

1,377,731.

Specification of Letters Patent. Patented May 10, 1921.

Application filed April 24, 1920. Serial No. 376,892.

To all whom it may concern:

Be it known that I, HENRY H. SANFORD, a citizen of the United States of America, residing at Mansfield, in the county of Rich-
5 land and State of Ohio, have invented cer-
tain new and useful Improvements in Com-
bined Gaseous and Solid Fuel Ranges, of
which the following is a specification.

The present invention relates to a com-
10 bined gaseous and solid fuel range.

The object of the present invention is to
provide a range or other heating apparatus
that will permit the operator to use solid
fuel or gaseous fuel as desired without mak-
15 ing it necessary to remove any of the parts,
insert any extra parts or otherwise change
the range except by shifting of a damper or
the like.

The present invention consists in provid-
20 ing a combined gaseous and solid fuel range
in which means are provided to direct the
course of travel of the products of combus-
tion of the solid fuel through flues ar-
ranged substantially around the oven and
25 thence out through the ordinary vent or
chimney flue and to construct said range so
as to provide means for directing the course
of travel of the products of combustion of a
gaseous burner in an independent path into
30 the oven and from the oven, thence under-
neath the oven to the ordinary vent or flue
pipe, the change being effected by adjusting
a single damper to open or closed position
in the oven.

35 These and other objects are attained by
the mechanism illustrated in the accompan-
ying drawing in which:

The figure is a side elevation of the range
showing the construction, arrangement and
40 assembly of the parts.

In the drawings reference numeral 1 rep-
resents the supporting structure of a stove
or range, 2 the top, 3 the outer wall of the
fire box and 4 the inner wall of the fire box.
45 To burn solid fuel a grate 5 is secured to the
coal fire box 6 and mounted therein in any
conventional manner. The inner wall 4 of
the fire box is provided with a pivoted
damper 7 which can be operated to open or
50 close the combustion chamber 8 to prevent
the heat from the solid fuel from escaping
through the opening 18. The oven 9 is
mounted in any conventional manner within
the compartment 10 so as to provide flues 11,
55 12 and 13 substantially surrounding the
oven. The end wall 14 of the oven provides

one wall of the combustion chamber and the
inner fire box wall 4 provides the other and
the flanges 15 and 16 complete the combus-
tion chamber 8. The flanges can be made 60
integral with the oven or attached thereto
as found most desirable.

A burner 17 is mounted in the combus-
tion chamber and it preferably extends
across the entire width of the chamber as 65
shown in the figure. Beneath the burner 17
body portion is cut away to provide an open-
ing 18 for the purpose of permitting the air
to enter into the chamber and mix with the
gaseous fuel and to permit the removal and 70
insertion of the burner conveniently. Adjacent
to the top of the oven end wall 14 an
opening 19 is provided through which the
products of combustion from the gaseous
burner enter the oven. Adjacent to the bot- 75
tom of the oven an adjustable damper 20 is
provided to permit the escape of the prod-
ucts of combustion from the burner into the
flue 12; thence underneath the oven through
flue 13 around the baffle plate 21 and out 80
through the vent or chimney flue 22.

The operation of the combined gaseous
and solid fuel range is as follows:

When it is desired to use solid fuel the
damper 7 is preferably closed. The prod- 85
ucts of combustion of the solid fuel passes
from the fire box 6 through the flues 11, 12
and 13 around the baffle plate 21 and out
through the vent or chimney flue 22. The
damper 20 is closed during the burning of 90
solid fuel to prevent the products of com-
bustion from the solid fuel from entering
the oven. In the use of gaseous fuel the
dampers 7 and 20 are adjusted to open posi- 95
tion and the products of combustion from
the burner pass into the oven through the
opening 19 and out through the damper 20
to the flue 13 underneath the oven around
the baffle plate 21 and escape through the
vent or chimney flue 22. 100

I claim:

1. In a combined gaseous and solid fuel
stove, an oven secured within the stove hav-
ing communicating flues surrounding the
oven except at one end, said end being spaced 105
apart from and secured to and in close prox-
imity to the fire box to form an independent
flue, means to close the top of the last men-
tioned flue, a damper secured in said flue, a
burner for gaseous fuel located at the bot- 110
tom of said flue.

2. In a combined gaseous and solid fuel

stove, an oven secured within the stove having communicating flues surrounding the oven except at one end, said end being spaced apart from and secured to and in close proximity to the fire box to form an independent flue, means to close the top of the last mentioned flue, a damper secured in said flue, being adapted to close off a por-

tion of said flue when solid fuel is being burned and opened when gaseous fuel is being burned, a burner for gaseous fuel located in said flue, a flue and deflector being located beneath the oven.

In testimony whereof I affix my signature.

HENRY H. SANFORD.
